AIR FLOW DEVICES

Jack W. Kice, John M. Redmond, Jr., and Charles D. Mattingly, Wichita, Kans., assignors to The Coleman Company, Inc., Wichita, Kans., a corporation of Kansas

Application June 27, 1952, Serial No. 296,014

3 Claims. (Cl. 98—38)

This invention relates to air flow devices and to a flexible resilient duct employed therewith. The invention is particularly useful in the mixing of air streams within an air flow device mounted within a hollow wall, as, for example, between stud spaces within a wall. Other uses of the invention will be apparent.

In apparatus heretofore employed for the mixing of currents of air with room air, as, for example, mixing a stream of highly heated air with room air or heating a stream of chilled air with room air, air noises in the mixing device have presented a serious problem. Further, in some installations the sound due to the blower is accentuated in the extended duct and head structures. Further, due to the rigid structure of the mixing duct and the heads therefor, it has been necessary to cut through the entire wall to provide a space for the insertion of the metal cabinet or mixer casing. Adjusting the length of the mixer cabinet to meet the demands of a room which is to be heated or the structure of the wall in which the device is to be fitted have also presented problems.

An object of the present invention is to provide a structure in which a flexible duct is employed which dampens air noises due to the turbulent flow of air streams and sounds due to the blower, while at the same time providing a structure which may be readily installed and involving a minimum of cutting of the wall space. Yet another object is to provide in such a blender or air mixing device a flexible duct which may be collapsed and drawn within a narrow opening in the wall to reach a lower outlet in the wall, the duct being so formed and being resilient so as to spring into a shape substantially fitting the wall space when released within the interior of the wall. Yet another object is to provide a method and means for forming a duct useful for these purposes and which may be readily collapsed, but upon being released will assume a predetermined open position. Other specific objects and advantages will appear as the specification proceeds.

The invention is shown in an illustrative embodiment, by the accompanying drawings, in which—

Fig. 1 is a perspective view of a wall structure receiving an air mixing device embodying our invention; Fig. 2, a view similar to Fig. 1 but showing the flexible duct being inserted into an opening in the wall; Fig. 3, a view showing the cabinet installed within the stud space of a wall; Fig. 4, a perspective view of a flexible duct embodying our invention; Fig. 5, a plan view of a mat of material prior to the forming of the same into a duct, perforations being formed in the mat along the lines of fold; Fig. 6, an enlarged broken detail sectional view showing the perforation through the mat; Fig. 7, a view similar to Fig. 6 but showing the mat bent at the point of the perforation; and Fig. 8, a broken perspective view of a modified form of mat structure showing the mat bent along a perforated line.

In the illustration given, 10 designates a lower duct head or inlet box formed of metal or other suitable material. An inlet pipe 11 extends through the lower end of the box or head 10 and may be provided with a control

2

damper 12. The box is provided with an upwardly-extending neck portion 13 which may be equipped with outwardly-struck teeth or lugs 14. The front of the box may be provided with a grille 15.

5 At the top of the mixer device is an outlet head or box 16 which may be provided with turning vanes 17, if desired, and the front of the head may be provided with a grille 18. The box is provided with a downwardly-extending neck portion 19, as shown more clearly in Fig. 2. The headers 10 and 16 are shown in greater detail in the co-pending application of Jack M. Kice, Serial No. 193,477, filed November 1, 1950, but in the present structures we terminate the necks 13 and 19 as indicated in dotted lines in Fig. 1.

10 15 In the practice of the present invention, we connect the neck 13 of the head 10 and neck 19 of the head 16 by a flexible duct 20.

The flexible duct 20 in the illustration given is formed of glass fibers and is fabricated as shown more clearly in Figs. 4 and 5. A mat or batt of glass fibers 21 is perforated along the fold lines 22, 23, 24, and 25, as illustrated in Fig. 5, and then the mat is folded into the rectangular shape shown in Fig. 4. The flap portion 26 is then connected to the adjacent side by the use of staples 27, as 20 25 shown more clearly in Fig. 4.

20 By forming short cuts or perforations 28 in the batt 21, as illustrated in Figs. 6, 7, and 8, we found that the batt could be shaped in the rectangular form illustrated in Fig. 4 without substantially weakening the duct structure. 30 The perforation 28, as illustrated in Fig. 7, permits a hinging action at each corner of the rectangular duct 20 and the resilient glass fiber structure tends to assume the rectangular shape shown in Fig. 4, when it is released. In other words, the natural resiliency of the fiber structure causes it to spring outwardly, when released from compression, to the shape shown in Fig. 4, and the perforations along the fold lines enable the structure to maintain the substantially rectangular shape illustrated.

35 40 It will be understood that the duct 20 may be formed of other suitable material which is flexible and resilient. Various types of treated fibers which render them sound-absorbing and resistant to heat while also providing thermo-insulation, may be employed. We prefer to employ glass fibers because of their unusually good sound-absorbing qualities, high thermo-insulation and resilience, the resilience being sufficient to cause the structure, after it has been collapsed, to spring back into an open duct-like position. If desired, the glass fibers may be bonded with a suitable resin, such as, for example, a phenol-formaldehyde condensation resin, etc.

45 50 The flexible duct 20 may be secured to the necks of the headers 10 and 16 by any suitable means. Adhesive may be employed if desired to fix the ends of the duct 20 to the necks 13 and 19. If desired, the metal body of the neck may be struck outwardly to provide thongs or barbs 14 which tend to hold the flexible duct 20 in position, as illustrated in Fig. 4 or, if desired, a metal or fiber strap 29 may be drawn about each end of the duct 20 adjacent the necks 13 and 19 and the strap secured by a suitable clamp 30.

55 60 The air mixer device may be installed between the stud spaces of a wall, as the building is being fabricated, as illustrated in Fig. 3; the duct 20 fits between the studs 31, and the heads 10 and 16 project forwardly so that when the inner wall of the room is constructed the inlets and outlets communicate with the room space.

65 70 In buildings already constructed, it is merely necessary to form an upper opening 32 and a lower opening 33, as shown more clearly in Fig. 2. The flexible duct 20 may be drawn through one opening and downwardly or upwardly to the next opening and the heads 10 and 16

secured to the ends of the duct. In actual practice, we prefer to connect the upper head 16 to one end of the duct and then to draw the duct downwardly to the bottom of the stud space and secure the bottom head 10 to the bottom of the duct. Where barbs 14 are employed, this connection is made almost automatically. Since the upper head 16 was connected to the upper end of the duct 20 at an earlier stage, this connection can be very conveniently and securely made. In some instances, it has been found very convenient to first place the flexible duct 20 within a sack which compresses the duct 20. The sack is drawn through the wall openings and then drawn away after the flexible duct has been drawn into position.

In each of the operations, after the duct 20 has been drawn into the rectangular stud space, the resilience of the duct causes it to spring outwardly into open position substantially filling the stud space and lying in a substantially rectangular form, as illustrated in Figs. 3 and 4.

The flexible duct 20 may be collapsed readily and rolled in the collapsed form. In the shipping of the apparatus, the flexible duct 20 in rolled or flattened condition serves as a protective padding or packing for the parts so that the structure can be packed and shipped within a relatively small container. Later, when the structure is assembled and the duct 20 is brought into its final position within the stud space, the resilience of the glass fibers causes the duct to spring into open position and thus maintain itself as an open duct within the wall space.

In the modification shown in Fig. 8, we provide the duct 20 on its inner side with a metal foil liner 34. Such a liner may be formed of aluminum foil or any other suitable foil which facilitates air flow and, preferably, is heat reflective. Such a liner may, however, be omitted.

In the foregoing structure, the glass fiber stack serves not only the function of a sheet metal stack, but also is flexible and easy to handle and install; providing insulation, is fire-resistant; has high thermal efficiencies, has a low moisture content, is rot and vermin resistant, does not absorb odors, is noncorrosive, is vibration proof, is dimensionally stable, is expandable, is light weight, has good acoustics, and is resilient so that after folding it re-assumes its original shape. The resilient material permits quick installation while at the same time quickly reassuming its tube-like shape within the wall cavity.

While in the foregoing specification we have set forth a specific structure in considerable detail for the purpose of illustrating an embodiment of the invention, it will be understood that such details of structure may be varied widely by those skilled in the art without departing from the spirit of our invention.

We claim:

1. An air mixer casing adapted for installation within the hollow stud space of a room wall, comprising an elongated and generally rectangular casing providing an air mixer chamber therein, the walls of said casing being glass fibers and being resin impregnated, said casing being provided at the corner portions thereof with longitudinally spaced perforations, said air mixer casing also being flexible and bodily compressible so that at least the transverse dimensions thereof can be reduced to permit the same to be threaded through a generally restricted opening in a room wall and being also bodily resilient so that it restores itself automatically to original shape after a compression thereof to form an air mixer chamber within a hollow room wall.

2. The structure of claim 1, in which said casing is equipped interiorly thereof with a metallic foil liner.

3. In an air mixer device adapted for installation within a hollow room wall having spaced-apart openings communicating with the room space, a pair of duct heads having substantially opposing neck portions and providing respectively an air inlet and an air outlet for communication with spaced openings in a room wall, one of said duct heads being adapted to receive an air inlet pipe, an elongated and generally rectangular air mixer casing formed of glass fibers and providing an air mixer chamber therein, said casing being provided with perforations longitudinally spaced along the corner portions thereof and being adapted to be connected adjacent the ends thereof to the opposing neck portions of said duct heads, and means for securing said casing to said neck portions, said air mixer casing being bodily compressible so that the transverse dimensions thereof can be reduced to permit the same to be threaded through an opening in a room wall and being also bodily resilient so that it restores itself to original shape to form an air mixer chamber within a hollow room wall after being compressed.
